TROUSERS.

Application filed July 27, 1927. Serial No. 208,678.

Our invention relates to a new and useful improvement in trousers and it relates more particularly to a novel construction in the art of making trousers whereby the inner flap or buttonhole band or strip heretofore commonly employed on the front flap of trousers, is entirely eliminated and whereby, moreover, not only is said buttonhole band or strip eliminated but the front buttons of the trousers are also eliminated.

Our invention further relates to a novel construction in trousers whereby the front of the trousers is closed by means of a fastening device, preferably of a continuous character, such as described, for instance, in United States Letters Patent 1,219,881, secured to the inner surface of the flap at a suitable distance from the edge thereof so as to be entirely concealed from view.

Our invention further consists of a novel construction in trousers, whereby the flap of the trousers is reinforced or stiffened by means of a suitable interior lining ply or haircloth, or the like, and whereby the thus reinforced or stiffened flap is secured to the opposed edge of the front opening of the trousers, by means of a fastening device spaced a suitable distance inwardly of the free edge of the flap; said flap being caused to lie flat against the body of the trousers in all positions or postures of the wearer or of the user by virtue of the novel construction thereof.

For the purpose of illustrating our invention, we have shown in the accompanying drawings one form thereof which is at present preferred by us, since the same has been found in practice to give satisfactory and reliable results, although it is to be understood that the various instrumentalities of which our invention consists can be variously arranged and organized and that our invention is not limited to the precise arrangement and organization of the instrumentalities as herein shown and described.

In the accompanying drawing, in which like reference characters represent like parts

Figure 1 represents a front elevation of a fragmentary portion of trousers embodying our invention.

Figure 2 represents a similar view in elevation, showing the interior of the trousers.

Figure 3 represents a fragmentary view in front elevation similar to that shown in Figure 1, somewhat enlarged, however, and

with the outer cloth ply of the flap cut away in order to expose to view the novel interior construction thereof.

Figure 4 represents a section on line 4-4 of Figure 3, showing the construction of the flap.

Figure 5 represents a section on line 5-5 of Figure 3, also illustrating the construction of the flap and its relation to the body of the trousers.

In carrying out our invention, we provide along one edge of the front opening of the trousers a flap 1, having the same general external appearance as the flaps employed heretofore on trousers, but being merely of a single fold and devoid of any buttonhole strip or buttonholes. The flap 1 is preferably formed of the cloth 2 of the trousers, folded back upon itself at 3 to form the back ply of the flap 1.

Between the body 2 of the cloth and the back ply 4 of the flap 1, a ply of stiffening fabric 5 is positioned, preferably the entire length of the flap, which may be haircloth or any other suitable stiffening fabric. The strands or threads of the stiffening fabric are preferably arranged parallel and at right angles respectively to the edge of the flap so as to impart to said flap the desired resiliency or stiffness transversely. Haircloth is preferable because it may be arranged with the relatively stiff hair strands extending transversely of the flap, and with the limp cotton threads thereof longitudinally of the flap, thereby retaining longitudinal limpness in the flap. The innermost edge 6 of the flap is suitably stitched so as to confine the haircloth or other stiffening medium within the flap.

The front half 7 of the trousers which is fastened to the other front half 8, underneath the flap 1, is made of any suitable construction or finish similar to the finish employed on trousers made heretofore. To the edge 9 of the front half 7 of the trousers, and longitudinal thereof, one half of a suitable fastening device is secured, such as, for instance, the fastening device described in United States Letters Patent No. 1,219,881. It is to be understood, however, that any other similar fastening device may be employed. The opposed and co-operating half 11 of the fastening device is secured longitudinally and in juxtaposition to the half 10, to the inner surface of the rein-

forced or stiffened flap 1, preferably near the inner edge thereof.

By uniting the two halves 10 and 11 of the fastener, the trouser will be joined in the front along a vertical line spaced inwardly a distance from the free edge 3 of the flap and substantially parallel thereto.

Due to the construction of the flap 1, and particularly due to the reinforced or stiffened character thereof, said flap will follow the portion 7 of the trousers and will lie flat against the same in all postures of the wearer, thus giving a neat and dressed appearance to the front of the trousers.

15 Due to the novel relation of the fastening means and the construction of the flap, said flap will have no tendency to spread open or buckle when the trousers are in use, both of which disadvantages the trousers of present construction so conspicuously possess.

The above novel construction in trousers, not only produces a front closure of a superior quality and appearance, and free of certain defects of trousers made heretofore 25 but said novel construction in trousers also substantially reduces the material and labor heretofore consumed in finishing the front portion of trousers, with a corresponding saving in the ultimate cost thereof.

30 By the above novel construction in trousers, moreover, the appearance of the front of the trousers is further enhanced by the fact that the flap 1 is considerably thinner and is composed of fewer layers or plies than the 35 flaps heretofore employed on trousers, and by virtue of the fact that the buttonhole strip or inner flap as well as the individual buttons are entirely eliminated. It is to be understood that while this novel construction 40 has been described merely in relation to trousers, that the same novel construction is applicable to other garments as well where overlapping edges of two parts of a garment must be fastened and a neat 45 appearance is required.

It should be understood therefore that the characteristic features of this novel construction are the overlapped parts of the garment, the inner one being limp while the 50 outer one being suitably stiffer and having a fastening device thereto and spaced a suitable distance inwardly of the free edge of the outer stiffened part, so as to leave said outer stiffened part of "flap" free to 55 assume any shape or conformation while in use.

It will now be apparent that we have devised a novel and useful construction which embodies the features of advantage enumerated as desirable in the statement of the invention and the above description and while we have in the present instance shown and described the preferred embodiment thereof which has been found in practice to give 60 satisfactory and reliable results, it is to be

understood that the same is susceptible of modification in various particulars without departing from the spirit or scope of the invention or sacrificing any of its advantages.

Having thus described our invention what we claim as new and desire to secure by Letters Patent is:—

1. Trousers or the like, comprising two separable parts having their adjacent edges in overlapping relation to each other, thereby forming an outer flap, continuous and separable fastening means extending longitudinally of said flap along the inner face thereof, having one part thereof secured to said outer flap, spaced inwardly a suitable distance from the free edge of said outer flap and having the other part thereof secured to the juxtaposed separable part of the trouser, an operating slide common to the two parts of said continuous fastening means, slidably carried thereby; said continuous fastening means and operating slide being concealed from view by said outer flap, and a textile stiffening ply in said outer flap intermediate the continuous fastening means and the free edge thereof, adapted to prevent the separation of said outer flap from the juxtaposed part of the trouser, along the free edge of said outer flap, when the fastening means is closed. 80

2. Trousers or the like, comprising two separable parts having their adjacent edges in overlapping relation to each other, thereby forming an outer flap, continuous and separable fastening means extending longitudinally of said flap along the inner face thereof, having one part thereof secured to the inner face of said outer flap, spaced inwardly a suitable distance from the free edge of said outer flap and having the other part secured to the juxtaposed separable part of the trouser, an operating slide common to the two parts of said continuous fastening means and slidably carried thereby; said continuous fastening means and operating slide being concealed from view by said outer flap, and a textile stiffening ply in said outer flap intermediate of said separable fastening means and the free edge thereof, being adapted to prevent the separation of said outer flap from the juxtaposed part of the trouser, along the free edge of said outer flap when said fastening means is closed. 90

3. Trousers or the like, comprising two separable parts having their adjacent edges in overlapping relation to each other, thereby forming an outer flap, continuous and separable fastening means extending longitudinally of said flap along the inner face thereof, having one part thereof secured to said outer flap, spaced inwardly a suitable distance from the free edge thereof and having the other part thereof secured to the juxtaposed part of the trouser, an op- 100

erating slide common to the two parts of said continuous fastening means, slidably carried thereby; said continuous fastening means and operating slide being concealed from view by said outer flap, and a haircloth stiffening ply in said outer flap, intermediate of said fastening means and the free edge thereof, said haircloth stiffening ply having strands of a limp character extending longitudinally and being relatively stiffer transversely than longitudinally of said flap. 10

In witness whereof we have hereunto set our hands.

ARTHUR S. LICHTEN.
